UNITED STATES PATENT OFFICE.

CHARLES E. JENKINS, OF NEW CASTLE, PENNSYLVANIA, ASSIGNOR TO THE HOWLING
TOM CATS OF AMERICA, OF NEW CASTLE, PENNSYLVANIA, A CORPORATION OF
PENNSYLVANIA.

DESIGN FOR A FEZ OR SIMILAR ARTICLE.

Application filed June 11, 1924. Serial No. 9,859. Term of patent 7 years.

To all whom it may concern:

Be it known that I, CHARLES E. JENKINS, a citizen of the United States, residing at New Castle, in the county of Lawrence and State of Pennsylvania, have invented a new, original, and ornamental Design for a Fez or Similar Article, of which the following is a specification, reference being had to the

accompanying drawing, forming part thereof.

The figure is a perspective view of a fez showing my new design.

I claim:

The ornamental design for a fez or similar article, as shown.

CHARLES E. JENKINS.
